DETACHABLE SEAT FOR A PICNIC BENCH OR SIMILAR ARTICLE

Dillon C. Yeagley, 1737 S. Liberty Ave.,
Alliance, Ohio 44601

Filed Nov. 19, 1965, Ser. No. 88,154

Term of patent 14 years

(Cl. D15—8)

I claim:

The ornamental design for a detachable seat for a picnic bench or similar article, as shown.
